G. E. SOVEREIGN

TRAFFIC SIGNAL

Filed April 16, 1921

UNITED STATES PATENT OFFICE.

GEORGE E. SOVEREIGN, OF PLAINFIELD, NEW JERSEY.

TRAFFIC SIGNAL.

Application filed April 16, 1921. Serial No. 461,771.

To all whom it may concern:

Be it known that I, GEORGE E. SOVEREIGN, a citizen of the United States, residing at Plainfield, in the county of Union and 5 State of New Jersey, have invented a new and useful Traffic Signal, of which the following is a specification.

The device forming the subject matter of 10 this application is a traffic signal, adapted to be placed on the surface of a roadway, and to be moved readily from one location to another, as desired.

The invention aims to provide a signal, 15 the casing portion of which will be effective in resisting shocks, deflecting vehicle wheels, and protecting the enclosed source of light.

The invention aims to provide a traffic 20 signal, the casing of which will be adequately ventilated, and, at the same time, be practically weather proof.

It is within the province of the disclosure, 25 to improve generally, and to enhance the utility of, devices of that type to which the invention appertains, divers points of novelty and utility being brought out, as the description proceeds.

Within the scope of what is claimed, a 30 mechanic may make changes in the structure shown and described, without departing from the spirit of the invention.

In the drawings:—Figure 1 shows in 35 elevation, a device constructed in accordance with the invention; Figure 2 is a bottom plan.

The casing portion of the signal may be 40 made out of any strong material, metal being preferred—although, possibly, glass or some other substance may be used. The casing includes a conical body 1 including a base 2, which may be in the form of a spider, having openings 3. A stem 4 depends from the base 2, and is adapted to be mounted removably in a support 5, of any desired sort. The support 5 may be the surface of a roadway. 45 In the lower edge of the body 1 there are openings 6, communicating, by way of the openings 3 in the base, with the interior of the body 1. The openings 6 admit air, for ventilation, and permit the egress of water, although, as pointed out hereinafter, it is not likely that water will find its way 50 within the body. There may be any desired number of the openings 6. As shown at 7, the lower surface of the base 2 is spaced slightly above the lower surface of the edge 55 of the body 1. This construction facilitates

drainage, and, also, aids in giving the body a firm seat, should the surface of the roadway or other support 5 be slightly irregular.

It is to be observed that the body or dome 60 1 is made up of an upper portion 8 and a lower portion 9, the upper portion defining a less acute angle with respect to the vertical, than does the lower portion 9. There are two advantages, which may be attributed 65 to this construction. First, the body is braced or trussed to withstand the shock of a blow from a vehicle wheel, an observation which will be appreciated readily, when the right hand side of Figure 1 is noted. Secondly, owing to the relative slants of the 70 parts 9 and 8, as shown at the left hand side of Figure 1, a vehicle wheel will mount the casing readily, and pass thereover, or be deflected therefrom, without exerting what 75 might otherwise be a crushing force.

The casing of the signal includes a closure 80 of any desired sort, such as a cap or closure 10 mounted on the body 1 and having a curved outer surface as indicated at 11, this 85 surface serving to deflect vehicle wheels, and to facilitate the passage of wheels with respect to the casing. The cap 10 has a depending neck 12 which is disposed vertically, the neck being received in the upper end of 90 the body 1. Because the neck 12 is disposed vertically, and at right angles to the direction in which a blow is imparted by a vehicle wheel, it will be practically impossible for the cap 10 to be knocked off by the wheel 95 axle, or any other part of a vehicle. The cap 10 has a central chamber 14, the cap being provided with any desired number of lateral openings 15. The openings 15 provide ventilation, and serve as an exit for the 100 heated air or products of combustion. The openings 15 slant downwardly and outwardly, as shown at 16 in Figure 1 and, consequently, it will be exceedingly difficult for rain or snow to drive inwardly through the 105 openings 15, the openings being so located that they tend to shed the water outwardly.

The body 1 is provided with any desired 110 number of apertures 18, in which lenses 19 may be placed. The lenses may be of any form and the word "lens" should be taken to mean any sort of a transparent or translucent closure placed in the aperture. The openings 18, of course, constitute bulls' eyes for the passage of light.

The light for the signal may be supplied in any desired way. It may be expedient to

use a lantern 20 insertable and removable, when the cap 10 is displaced. Should it be considered expedient to light the signal electrically, conductors may be extended 5 through the openings 3 in the base 2. Any ordinary lamp may be used in place of the lantern 20.

The casing may be moved readily from place to place. It affords an adequate protection to the lantern 20 or other source of light. The device, considered as an article 10 of manufacture, may be turned out cheaply, and embodies no parts likely to get out of order.

15 I claim:—

A traffic signal comprising a casing including a tapered body having a base in the form of a spider provided with openings, the body being provided in its lower edge with openings communicating with the 20 openings in the spider, and the spider being provided with a depending stem, the body being supplied with an opening for the passage of light; and a closure seated detachably on the body, the closure having a 25 ventilating opening.

In testimony that I claim the foregoing as my own, I have hereto affixed my signature.

GEORGE E. SOVEREIGN.
